(57) **ABSTRACT**

A blade cartridge including one or more blades fixed between a platform member and a cap member. The present invention provides a novel blade cartridge including one or more protruding members, or guard ribs, positioned proximate the skin engaging edges of the blades such that a portion of the blade adjacent the guard ribs has a negative exposure. The guard rib preferably has an arcuate contact surface and is narrow in thickness in a direction along the skin engaging edge. Preferably a plurality of guard ribs are evenly positioned along the blade cartridge. In addition to the guard ribs on the platform member, the present invention further includes protruding members, or guard ribs, on the cap member. The guard ribs on the platform member are preferably aligned with and substantially continuous with the guard ribs on the cap member. In a further embodiment, the blade cartridge includes a spacer separating the first blade and a second blade. In this embodiment the spacer has protruding members, or guard ribs, positioned proximate the skin engaging edges of the first and second blades.

RAZOR BLADE CARTRIDGE WITH GUARD RIBS

This application is based upon Provisional Patent Application entitled "Virtual Guard Twin Blade Razor Cartridge" filed on Apr. 14, 1998, Ser. No. 60/081,589 with named inventor Jeffrey Wonderley, and upon Provisional Patent Application entitled "Virtual Guard Single Blade Razor Cartridge" filed on Apr. 17, 1998, Ser. No. 60/082,261 with named inventors Jeffrey Wonderley and Gregory McCool.

BACKGROUND OF THE INVENTION

The present invention relates to wet shaving systems of the blade type and more particularly to a shaving system having one or more blades positioned within a blade cartridge and having cutting edges protected by guard ribs.

Shavers have long sought a wet shaving system that provides a smooth and comfortable shave without causing annoying cuts and abrasions on the skin of the shaver. In many instances the blade being at the wrong blade exposure or an improper shaving angle causes cuts and abrasions.

The terms "blade exposure" and "shaving angle" represent geometrical relationships between the blade and the shaving surface. These terms as well as another term commonly used in the art are defined as follows. First, the term "shaving plane" means the plane tangent to skin engaging surfaces, referred to as a guard and a cap, which are disposed on both sides of the blade so as to engage the shaving surface before and after engagement by the blade. Second, the term "blade exposure" means the distance by which the blade edge projects forward of the shaving plane. Third, the term "shaving angle" means the acute angle between a plane tangent to the cutting edge of the blade and the shaving plane.

Various approaches have been used in an effort to present a blade cartridge having the correct blade exposure and shaving angle. One approach disclosed in related art patents includes the configuration of a blade cartridge having blades that are movably mounted therein such that when force is applied to the blades they move to a less aggressive blade exposure and shaving angle. A second approach is to pivotally mount the blade cartridge to a handle that allows the entire cartridge to rotate in response to shaving forces to a less aggressive blade exposure and shaving angle.

A third approach involves constructing a blade cartridge wherein the blade assembly, including the blades, a spacer, and a cap member, are movable as a unit between various blade exposures and shaving angles within various degrees of control and direction in response to forces encountered during shaving. For example, Ciaffone et al., U.S. Pat. No. 4,461,079, describes a razor cartridge comprising a body portion 10 which includes a guard bar 12 (FIGS. 1-5). The guard bar 12 defines a leading skin-engaging surface fixed to the body portion. Rear beam 17 spans end walls 14 and 16 of the body portion 10 and a medial support member 13 to join the front of the cartridge 12 to the end thereof. A plurality of generally flat coplanar segments 18, 19, 21, and 22, each having an opening 23, are hinged to the rear beam 17 by mating webs 24, 26, 27, and 28 (col. 2, lines 50-52). Collectively, the segments 18, 19, 21, and 22 define a blade seat which is operable to pivot about the beam 17, thereby changing the attitude of blade edge relative to guard bar 12 (col. 2, lines 53-57). A cap 33 is apparently placed above an assembly of two skin-engaging blades 34 and 36 straddling a spacer 37 (FIG. 3). The two blades and the spacer are secured to one coplanar segment 21 of the blade support or

blade seat by a conventional rivet 38 to form a rigid unit. A hinge 27 connects the coplanar segment 21 to the rear-beam 17 (col. 3, lines 1-8). As compared to the position of the blade edges relative to the guard bar at the normal or free position set in accordance with a predetermined blade geometry (FIG. 3), a change in blade geometry occurs during the course of shaving when a shaving force F causes the blade package to rotate or pivot about rear-beam 17 in the direction of arrow R where the blade edges are rendered less "aggressive" (FIG. 4, col. 3, lines 13-23). Upon relaxation of shaving forces, the elastic memory of hinges 24, 26, 27, and 28 forces the blade seat, and therefore the blade edges, to return to their normal position (FIG. 3, col. 3, lines 24-26).

Other approaches include foil guarded cartridges, taped blades and wire wrapped blades or cartridges. Foil guarded cartridges are typically constructed with a piece of foil extending over the cap member, the blades and the platform member. The foil has openings adjacent the blade edges to allow the blade edge to contact the skin of the shaver. Taped blades include a piece of material extending from the upper surface of the blade over the blade edge to the lower surface of the blade. The material has openings positioned along the blade edge to allow the blade edge to contact the skin of the shaver. Wire wrapped blades include a piece of wire extending around the entire blade and over the blade edge. Alternatively, the piece of wire can be wrapped around the entire blade assembly and over the blade edges, to form a wire wrapped blade cartridge.

The various approaches discussed above present several different problems. First, the cost of manufacturing these blade cartridges is high. The relatively complex mechanisms used to produce blade cartridges having movable blades or movable blade assemblies significantly increases the cost to produce and assemble such blade cartridges. Similarly, wire wrapped, foil guarded and taped blades are difficult and expensive to assemble adding cost to the finished product.

A second problem with the movable blade cartridges described above is the delicate, and sometimes unpredictable, nature of the movable blades. By movably mounting a blade within a blade cartridge, the risk arises that the blade may move to a more aggressive blade exposure or shaving angle, thereby cutting the shaver. Additionally, by movably mounting a blade within a blade cartridge, the risk arises that the movable connection may fail and the blade may become dislodged from the blade cartridge.

A second problem with the wire wrapped, foil guarded, and taped blade approaches is that they tend to grab and pull whiskers that become caught between the protective member and the blade. They also tend to collect debris and are hard to flush clean. The foil guarded, taped blade, and wire wrapped cartridges are limited in how close of a shave they can produce by the thickness of the foil, tape, or wire (diameter) used to cover the blades. The wire wrapped blades have the disadvantage that the wire tends to embed itself into the blade thereby damaging the blade. Additionally, the wires are easily disturbed thereby effecting shaving characteristics of the blade and potentially causing wear on the blade edge.

Consequently, a need exists for a blade cartridge incorporating an effective means for preventing cuts and abrasions caused by a razor blade being repeatedly passed over the skin of a shaver. The blade cartridge should be constructed to provide proper blade exposure and shaving angle, while still providing a close shave. The blade cartridge should also be cost effective to manufacture and durable. In

addition, the blade cartridge should be configured to effectively shave varying contours and surfaces.

SUMMARY OF THE INVENTION

The present invention provides a novel blade cartridge designed to satisfy the aforementioned needs. The invention embodies one or more blades fixed between a platform member and a cap member. The blade cartridge has one or more protruding members, or guard ribs, positioned proximate the skin engaging edges of the blades such that a portion of the blade adjacent the guard ribs has a negative exposure. The guard ribs provide an effective means for preventing cuts and abrasions caused by a razor blade being repeatedly passed over the skin of a shaver. The guard ribs provide portions of the skin engaging edges with a negative blade exposure that prevents overexposure of the blades to the skin, while allowing the remainder of the skin engaging edges of the blade to still provide a close shave. The blade cartridge is cost effective to manufacture and durable, in that the present invention provides a simple arrangement without moving parts. In addition, the blade cartridge is configured to provide an effective shave on a variety of contours and surfaces.

Accordingly, the present invention relates to a blade cartridge including a platform member having a blade seat and a guard member. The guard member is located forward of and parallel to the blade seat so as to form a longitudinal slot between the blade seat and the guard member. The blade cartridge also includes a primary blade that is disposed on the blade seat such that the cutting edge of the blade is located rearwardly of the guard member. The primary blade may include a forward section having an aperture array defining a flow path. Preferably, the cutting edge of the primary blade is parallel to the guard member.

The blade cartridge includes a cap member disposed on the primary blade. The cap member may include an open portion abutting the aperture in the primary blade that allows the free flow of debris through the resulting flow path and out the bottom of the blade cartridge. The cap member secures the members forming the blade cartridge together. The blade cartridge may include a lubrication strip integral with the cap.

Preferably, the blade cartridge is connected to a handle, and can be detachably connected so as to allow the blade cartridge to be replaced when it becomes worn. Alternatively, the blade cartridge may be permanently mounted on or integrally attached to a handle in the form of a disposable razor.

The present invention further includes one or more protruding members, or guard ribs, evenly positioned along the blade cartridge. The guard ribs preferably each have an arcuate contact surface and are narrow in thickness in a direction along the skin engaging edge. In addition to the guard ribs on the platform member, the present invention preferably further includes protruding members, or guard ribs, on the cap member. The guard ribs on the platform member are preferably aligned with and substantially continuous with the guard ribs on the cap member.

In a further embodiment, the blade cartridge includes a secondary blade and a spacer separating the primary blade and the secondary blade. In this embodiment the spacer preferably has protruding members, or guard ribs, positioned proximate the skin engaging edges of the secondary blades. In this embodiment the spacer preferably has an open portion abutting the aperture in the primary blade that allows debris to flow through the resulting flow path and out the

bottom of the blade cartridge. As with previous embodiments, the guard ribs on the spacer are preferably aligned with and substantially continuous with the guard ribs on the cap member and the platform member. Similarly, 5 additional spacers with protruding members and additional blades may be added to the blade cartridge to produce further embodiments.

The invention itself, together with further objects and advantages, will best be understood by reference to the 10 following detailed description taken in conjunction with the accompanying drawings.

BRIEF DESCRIPTION OF THE DRAWINGS

FIG. 1 is a top perspective view of a first embodiment 15 having twin blades of a razor blade cartridge according to the present invention.

FIG. 2 is a bottom perspective view of a first embodiment 20 having twin blades of a razor blade cartridge according to the present invention.

FIG. 3 is a bottom perspective view of a first embodiment 25 having twin blades of a razor blade cartridge according to the present invention.

FIG. 4 is a top plan view of a first embodiment having 30 twin blades of a razor blade cartridge according to the present invention.

FIG. 5 is a bottom plan view of a first embodiment having twin blades of a razor blade cartridge according to the present invention.

FIG. 6 is a side view, including phantom lines, of a first 35 embodiment having twin blades of a razor blade cartridge according to the present invention.

FIG. 7 is a cross-sectional view along a rivet of a first embodiment having twin blades of a razor blade cartridge according to the present invention.

FIG. 8 is a cross-sectional view of a first embodiment 40 having twin blades of a razor blade cartridge according to the present invention.

FIG. 9 is a cross-sectional view along a rivet of a second embodiment having twin blades and continuous guard ribs of a razor blade cartridge according to the present invention.

FIG. 10 is a top perspective view of a third embodiment 45 having a single blade of a razor blade cartridge according to the present invention.

FIG. 11 is a top plan view of a third embodiment having a single blade of a razor blade cartridge according to the present invention.

FIG. 12 is a bottom plan view of a third embodiment 50 having a single blade of a razor blade cartridge according to the present invention.

FIG. 13 is a side view, including phantom lines, of a third embodiment having a single blade of a razor blade cartridge according to the present invention.

FIG. 14 is a cross-sectional view along a rivet of a third embodiment having a single blade of a razor blade cartridge according to the present invention.

FIG. 15 is a cross-sectional view of a third embodiment 60 having a single blade of a razor blade cartridge according to the present invention.

FIG. 16 is a cross-sectional view along a rivet of a fourth embodiment having a single blade and continuous guard ribs of a razor blade cartridge according to the present invention.

FIG. 17 is a top perspective view of a fifth embodiment 65 having a single blade and no guard member of a razor blade cartridge according to the present invention.

FIG. 18 is a side view, including phantom lines, of a fifth embodiment having a single blade and no guard member of a razor blade cartridge according to the present invention.

FIGS. 1 through 18 are presented by way of illustration and not by limitation to depict the preferred embodiments of the present invention. Embodiments including the various aspects of the present invention will now be described in detail with reference to the accompanying drawings.

DETAILED DESCRIPTION OF THE INVENTION

Turning now to the drawings, FIGS. 1-8 illustrate a first embodiment 10 of a blade shaving cartridge ("BSC" or blade cartridge) or razor head, FIG. 9 illustrates a second embodiment 12, FIGS. 10-15 illustrate a third embodiment 14, FIG. 16 illustrates a fourth embodiment 16, and FIGS. 17 and 18 illustrate a fifth embodiment.

Referring to FIGS. 1-8, the first embodiment of the present invention includes a platform member 20, a primary blade 60, a spacer 80, a secondary blade 100, and a cap member 120. As depicted in FIGS. 7 and 8, the platform member 20 includes a blade seat 22 having a front wall 24 and a rear wall 26. The guard member 30 extends parallel to the front wall 24 forming a flow channel or slot 34 between the guard member 30 and the front wall 24. The guard member 30 is connected to the front wall 24 by a plurality of support members 36, which extend substantially perpendicular to the longitudinal axis of the both the guard member 30 and the front wall 24. The guard member 30 placed in front of the first blade 60 is integral with the platform member 20 and is therefore stationary relative to the blade cartridge 10. The guard 30 being positioned in front of the first blade 60 has a raised skin engaging portion 32, which provides an engaging surface to control exposure of the first blade 60 to the shaver's skin.

The support members 36 extend downwardly away from the upper surface 38 of the blade seat 22 so as to create a gap 42 between a lower surface 64 of the first blade 60 and the guard member 30. The gap 42 allows for the passage of water and shaving debris beneath the first blade 60, through the slot 34, and out the bottom of the blade cartridge 10.

The blade seat 22 includes an upper surface 38, as well as a plurality of securing apertures 40. The securing apertures 40 operate in conjunction with staking pins (or rivets) 122 located on the cap member 120 to permanently secure the platform member 20, the blades 60 and 100, the spacer 80, and the cap member 120 together.

The blade cartridge 10 includes a primary or first blade 60 and a secondary or second blade 100 each having substantially parallel front and rear edges with the front edge of each blade defining a skin engaging edge or cutting edge 62 and 102, respectively. Each blade 60 and 100 defines a longitudinal axis that is parallel to the cutting edge of the blade 60 and 100 and a lateral axis that is perpendicular to the cutting edge of the blade 60 and 100.

The first blade 60 is fixed between the upper surface 38 of the blade seat 22 and a lower surface 84 of the spacer 80. The first blade 60 has a lower surface 64 and an upper surface 66. The first blade 60 includes securing apertures 68 which align with the securing apertures 40 of the blade seat 22 so as to allow the staking pins 122 to pass through the securing apertures 68 of the first blade 60, thereby securing the first blade 60 to the blade cartridge 10. In the first embodiment the first blade preferably has a plurality of apertures 70 along the forward portion thereof that allow debris to travel through the apertures 70 and out the bottom of the blade cartridge 10.

The spacer 80 functions to separate blades 60 and 100. As depicted in FIGS. 7 and 8, the spacer 80 has an upper surface 86 and a lower surface 84. The spacer 80 includes securing apertures 88 which align with the securing apertures 40 of the blade seat 22 so as to allow the staking pins 122 to pass through the securing apertures 88 of the spacer 80, thereby securing the spacer 80 to the blade cartridge 10. The forward portion of the spacer 80 includes a plurality of passages 90. Preferably the passages 90 are recessed portions, as depicted in the figures, although other structures may be used such as channels.

Similar to the first blade 60, the second blade 100 includes securing apertures 108 which align with the securing apertures 40 of the blade seat 22 so as to allow the staking pins 122 to pass through the securing apertures 108 of the second blade 100, thereby securing the blade to the blade cartridge 10. The second blade 100 is fixed between the upper surface 86 of the spacer 80 and lower surface 124 of the cap member 120. The second blade 100 includes a lower surface 104 and an upper surface 106. As depicted in FIGS. 7 and 8, an opening 46 is formed between the lower surface 104 of the second blade 100 and the upper surface 66 of the first blade 60. The opening 46 and passages 90 define a flow path that allows debris to flow through the apertures 70 in the first blade 60 and exit the bottom of the blade cartridge 10. The opening 46 and passages 90 also allow the shaver to direct water through the bottom of the blade cartridge 10 and flush water and debris through the apertures 70 in the first blade 60 and out the opening 46.

The blades 60 and 100 of the present invention are positioned within the blade cartridge 10 beginning with the lower surface 64 of the first blade 60 being disposed on the upper surface 38 of the blade seat 22. The lower surface 84 of the spacer 80 is disposed on the upper surface 66 of the first blade 60. The lower surface 104 of the second blade 100 is disposed on the upper surface 86 of the spacer 80. The spacer 80 exhibits a uniform height so that when the blades 60 and 100 are secured to the upper surface 86 and lower surface 84 of the spacer 80, respectively, such that the blades 60 and 100 are parallel to one another. The lower surface 124 of the cap member 120 is disposed on the upper surface 106 of the second blade 100. FIGS. 7 and 8 illustrate the alignment of the first blade 60, the spacer 80, and the second blade 100. As depicted the cutting edge 62 of the first blade 60 is located forward of the cutting edge 102 of the second blade 100.

The cap member 120 includes an upper surface 128 that acts as a skin engaging surface as the blade cartridge 10 is passed over the skin of a shaver. The cap member 120 includes a plurality of staking pins 122, such as rivets. The staking pins 122 extend downwardly from the lower surface 124 of the cap member 120 and pass through the securing apertures 108 of the second blade 100, through the securing apertures 88 of the spacer 80, through the securing apertures 68 of the first blade 60, and into the securing apertures 40 of the blade seat 22. The ends of the staking pins 122 extend beyond the blade seat 22 and are upset (the staking pins 122 are depicted prior to upsetting the end thereof) thereby permanently affixing the blade seat 22, blades 60 and 100, spacer 80, and cap member 120 together. As a result of mounting the blades 60 and 100 in accordance with the present invention, there is no longitudinal movement of any of the blades 60 and 100 relative to the remainder of the blade cartridge 10.

Numerous variations of the blades 60 and 100 are possible. For example, each blade 60 and 100 may be tapered such that the thickness of the blade decreases in the direction

of the forward portion of the blade. Also, each blade **60** and **100** can comprise a U-shaped channel in the forward portion of the blades. Finally, additional holes can be added to the blades of the preferred embodiment.

In yet another variation, a shaving aid or lubrication applicator **130** may be affixed or included with the blade cartridge **10**. Typically the shaving aid **130** comprises a polystyrene-polyethylene oxide blend in the form of lubricating strip **132**, which may be affixed to the upper surface **126** of the cap member **120** behind the second blade **100**. During shaving, the polyethylene oxide bleaches out of the styrene matrix. The cap member **120** may have a lube strip **132** glued onto or molded onto the cap member **120** in a second shot. Preferably, the shaving aid **130** comprises a matrix of polystyrene, polyethylene oxide and aloe and/or vitamin E and/or other additives.

In yet a further variation, the blade cartridge **10** may be permanently or detachably connected to a handle by suitable structures formed on the bottom surface of the blade cartridge **10**. For example, as illustrated in FIGS. 7 and 8, the bottom surface of the platform member **20** includes a mounting device **50** that allows the blade cartridge **10** to be detachably mounted to a handle. The mounting device **50** includes a pair of mounting hooks **52** that form a slot **54** for mounting to a handle. Alternatively, the blade cartridge **10** may be integrally attached to a handle in the form of a disposable razor.

A novel feature of the present invention is the one or more protruding members, i.e., guard ribs, **140**, **142**, positioned proximate the skin engaging edges, i.e., with substantially no gap between the skin engaging edges of the blades and an end of protruding members **140**, **142**, of the blades such that a portion of the blade adjacent the guard ribs has a negative exposure. The guard member **30** of the platform member **20** includes a plurality of guard ribs **140** evenly spaced along the length of the blade cartridge **10**. Preferably, the guard ribs **140** each have an arcuate contact surface **141** and are narrow in thickness in a direction along the skin engaging edge **62** of the first blade **60**. Alternatively, however, the contact surface **141** may be configured to be planar or wide or have a varying width. The guard ribs **140** are positioned proximate the skin engaging edge **62** of the first blade **60** such that a portion of the first blade adjacent the guard ribs **140** has a negative exposure based on the shaving plane **2** depicted in FIG. 8. Proximal positioning of guard ribs **140** to the skin engaging edge **62** is best depicted in FIG. 6, which shows substantially no gap between an end of the guard ribs **140** and the skin engaging edge **62**. Proximal positioning of guard ribs **142** in relation to skin engaging edge **102** is also depicted in FIG. 6, which shows substantially no gap between an end of the guard ribs **142** and the skin engaging edge **102** of blade **100**. For example, the distance between the skin engaging edges **62**, **102** and ends of guard ribs **140**, **142** is minimal. The portions of the first blade **60** in between the guard ribs **140** are allowed to fully engage the skin of the shaver while the guard ribs **140** prevent overexposure of the skin to the cutting edge **62**.

In addition to the guard ribs **140** on the platform member **20**, the present invention further includes protruding members **142**, or guard ribs, on the spacer **80** and protruding members **144**, or guard ribs, on the cap member **120**. The guard ribs **142** on the spacer **80** are positioned spaced from the skin engaging edge **62** of the first blade **60**, as depicted in FIGS. 1, 4, and 6-8, and proximate to the skin engaging edge **102** of the second blade **100**. Proximal positioning of guard ribs **142** to the skin engaging edge **102** is best depicted in FIG. 6, which shows substantially no gap between an end

of the guard ribs **140** and the skin engaging edge **62**. In other words, the distance between the skin engaging edge **62** and ends of guard ribs **140** is minimal. The guard ribs **144** on the cap member **120** are positioned spaced from the skin engaging edge **102** of the second blade **100**, as depicted in FIGS. 1, 4, and 6-8. In the preferred embodiment the guard ribs **140** on the platform member **20**, the guard ribs **142** on the spacer **80**, and the guard ribs **144** on the cap member **120** are aligned such that they form evenly spaced rows along the length of the blade cartridge **10**. Alternatively, the guard ribs are not aligned in rows but rather are staggered or configured in some other pattern. The size and spacing of the guard ribs can be varied to achieve desired shave characteristics.

A second embodiment **12** of the present invention is depicted in FIG. 9. The second embodiment **12** is substantially identical to the first embodiment **10**, except that in the second embodiment **12** the guard ribs **150** on the platform member **20**, guard ribs **160** on the spacer **80**, and guard ribs **170** on the cap member **120** are aligned with each other and are substantially continuous. The guard rib **150** has a wall **152** that abuts a wall **162** on the guard rib **160** such that contact surfaces **151** and **161**, respectively, are flush and substantially continuous or continuous. Similarly, the guard rib **160** has a wall **164** that abuts a wall **172** on the guard rib **170** such that contact surfaces **161** and **171**, respectively, are flush and substantially continuous or continuous.

A third embodiment **14** of the present invention is depicted in FIGS. 10-15. The third embodiment **14** is substantially identical to the first embodiment **10**, except that the third embodiment **14** does not include a second blade or a spacer.

Referring to FIGS. 10-15, the third embodiment **14** of the present invention includes a platform member **220**, a primary blade **260**, and a cap member **320**. As depicted in FIGS. 14 and 15, the platform member **220** includes a blade seat **222** having a front wall **224** and a rear wall **226**. The guard member **230** extends parallel to the front wall **224** forming a flow channel or slot **234** between the guard member **230** and the front wall **224**. The guard member **230** is connected to the front wall **224** by a plurality of support members **236**, which extend substantially perpendicular to the longitudinal axis of the both the guard member **230** and the front wall **224**. The guard member **230** placed in front of the first blade **260** is integral with the platform member **220** and is therefore stationary relative to the blade cartridge **14**. The guard **230** being positioned in front of the first blade **260** has a raised skin engaging portion **232**, which provides an engaging surface to control exposure of the first blade **260** to the shaver's skin.

The support members **236** extend downwardly away from the upper surface **238** of the blade seat **222** so as to create a gap **242** between a lower surface **264** of the first blade **260** and the guard member **230**. The gap **242** allows for the passage of water and shaving debris beneath the first blade **260**, through the slot **234**, and out the bottom of the blade cartridge **14**.

The blade seat **222** includes an upper surface **238**, as well as a plurality of securing apertures **240**. The securing apertures **240** operate in conjunction with staking pins (or rivets) **322** located on the cap member **320** to permanently secure the platform member **220**, the blade **260**, and the cap member **320** together.

The first blade **260** is fixed between the upper surface **238** of the blade seat **222** and a lower surface **324** of the cap member **320**. The first blade **260** has a lower surface **264** and an upper surface **266**. The first blade **260** includes securing

apertures 268 which align with the securing apertures 240 of the blade seat 222 so as to allow the staking pins 322 to pass through the securing apertures 268 of the first blade 260, thereby securing the first blade 260 to the blade cartridge 14. In the third embodiment the first blade 260 has a plurality of apertures 270 along the forward portion thereof that allow debris to travel through the apertures 270 and out the bottom of the blade cartridge 14.

The cap member 320 includes an upper surface 328 that acts as a skin engaging surface as the blade cartridge 14 is passed over the skin of a shaver. The cap member 320 includes a plurality of staking pins 322, such as rivets. The staking pins 322 extend downwardly from the lower surface 324 of the cap member 320 and pass through the securing apertures 268 of the first blade 260, and into the securing apertures 240 of the blade seat 222. The ends of the staking pins 322 extend beyond the blade seat 222 and are upset (the staking pins 322 are depicted prior to upsetting the end thereof thereby permanently affixing the blade seat 222, blade 260, and cap member 320 together. As a result of mounting the blade 260 in accordance with the present invention, there is no longitudinal movement of the blade 260 relative to the remainder of the blade cartridge 14.

The forward portion of the cap member 320 includes a plurality of passages 327. Preferably the passages 327 are recessed portions, as depicted in the figures, although other structures may be used such as channels. The passages 327 define a flow path that allows debris to flow through the apertures 270 in the first blade 260 and exit the bottom of the blade cartridge 14. The passages 327 also allow the shaver to direct water through the bottom of the blade cartridge 14 and flush water and debris through the apertures 270 in the first blade 260.

The third embodiment 14 of FIGS. 11-15 may also include a shaving aid or lubrication applicator 330 in the form of lubricating strip 332 as described for the first embodiment 10. As in the first embodiment 10, the third embodiment may include a mounting device 250 that allow the blade cartridge 14 to be detachably mounted to a handle. The mounting device 250 includes a pair of mounting hooks 252 that form a slot 254 for mounting to a handle. Alternatively, the third embodiment 14 may be permanently or integrally mounted to a handle.

The third embodiment 14 also includes one or more protruding members 340 and 344, or guard ribs, positioned proximate the skin engaging edge of the blade such that a portion of the blade adjacent the guard ribs has a negative exposure. As in the first embodiment 10, the guard member 230 of the platform member 220 of the third embodiment 14 preferably includes a plurality of guard ribs 340 evenly spaced along the length of the blade cartridge 14. Preferably, the guard ribs 340 each have an arcuate contact surface 341 and are narrow in thickness in a direction along the skin engaging edge 262 of the first blade 260. The guard ribs 340 are positioned proximate the skin engaging edge 262, i.e., without a substantial gap as depicted in FIG. 14, of the first blade 260 such that a portion of the first blade adjacent the guard ribs 340 has a negative exposure based on the shaving plane 4 depicted in FIG. 15. The portions of the first blade 260 in between the guard ribs 340 are allowed to fully engage the skin of the shaver while the guard ribs 340 prevent overexposure of the skin to the cutting edge 262.

In addition to the guard ribs 340 on the platform member 220, the present invention further includes protruding members 344, or guard ribs, on the cap member 320. The guard ribs 344 on the cap member 320 are positioned spaced from

the skin engaging edge 262 of the first blade 260, as depicted in FIG. 14. In the preferred embodiment the guard ribs 340 on the platform member 220 and the guard ribs 344 on the cap member 320 are aligned such that they form evenly spaced rows along the length of the blade cartridge 14.

A fourth embodiment 16 of the present invention is depicted in FIG. 16. The fourth embodiment 16 is substantially identical to the second embodiment 12. In the fourth embodiment 16 the guard ribs 350 on the platform member 220, and guard ribs 370 on the cap member 320 are aligned with each other and are substantially continuous. The guard rib 350 has a wall 352 that abuts a wall 372 on the guard rib 370 such that contact surfaces 351 and 371, respectively, are flush and substantially continuous or continuous.

Referring to FIGS. 17 and 18, a fifth embodiment of the present invention includes a platform member 20, a primary blade 60, and a cap member 120. As depicted in FIGS. 17 and 18, the platform member 20 includes a blade seat 22 having a front wall 24 and a rear wall 26.

Support members 36 extend downwardly away from the upper surface 38 of the blade seat 22 so as to create a gap between a lower surface 64 of the blade 60 and the guard member 30. The gap allows for the passage of water and shaving debris beneath the first blade 60, through the slot 34, and out the bottom of the blade cartridge 10.

The blade seat 22 includes an upper surface 38, as well as a plurality of securing apertures 40. The securing apertures 40 operate in conjunction with staking pins (or rivets) 122 located on the cap member 120 to permanently secure the platform member 20, the blade 60 and the cap member 120 together.

The blade cartridge 10 includes a primary blade 60 having substantially parallel front and rear edges with the front edge of the blade defining a skin engaging edge or cutting edge 62. The blade 60 defines a longitudinal axis that is parallel to the cutting edge of the blade 60, and a lateral axis that is perpendicular to the cutting edge of the blade 60.

The blade 60 is fixed between the upper surface 38 of the blade seat 22 and a lower surface 124 of the cap member 120. The blade 60 has a lower surface 64 and an upper surface 66. The blade 60 includes securing apertures, not shown, that align with the securing apertures 40 of the blade seat 22 so as to allow the staking pins 122 to pass through the securing apertures of the blade 60, thereby securing the blade 60 to the blade cartridge 10.

The blade 60 of the present invention is positioned within the blade cartridge 10 beginning with the lower surface 64 of the blade 60 being disposed on the upper surface 38 of the blade seat 22. The lower surface 124 of the cap member 120 is disposed on the upper surface of the blade 60. FIGS. 17 and 18 illustrate the alignment of the blade 60.

The cap member 120 includes an upper surface 128 that acts as a skin engaging surface as the blade cartridge 10 is passed over the skin of a shaver. The cap member 120 includes a plurality of staking pins 122, such as rivets. The staking pins 122 extend downwardly from the lower surface 124 of the cap member 120 and pass through the securing apertures of the blade 60, and into the securing apertures 40 of the blade seat 22. The ends of the staking pins 122 extend beyond the blade seat 22 and are upset (the staking pins 122 are depicted prior to upsetting the end thereof) thereby permanently affixing the blade seat 22, blade 60, and cap member 120 together. As a result of mounting the blade 60 in accordance with the present invention, there is no longitudinal movement of the blade 60 relative to the remainder of the blade cartridge 10. A novel feature of the present

invention is the one or more protruding members, or guard ribs, 140, positioned proximate the skin engaging edge, i.e., with substantially no gap between the skin engaging edge 62 of the blade 60 and an end of protruding members 140, of the blade such that a portion of the blade adjacent the guard ribs has a negative exposure. The guard-member 30 of the platform member 20 includes a plurality of guard ribs 140 evenly spaced along the length of the blade cartridge 10. Preferably, the guard ribs 140 each have an arcuate contact surface 141 and are narrow in thickness in a direction along the skin engaging edge 62 of the blade 60. Alternatively, however, the contact surface 141 may be configured to be planar or wide or have a varying width. The guard ribs 140 are positioned proximate the skin engaging edge 62 of the blade 60 such that a portion of the blade 60 adjacent the guard ribs 140 has a negative exposure based on the shaving plane 2 depicted in FIG. 18. Proximal position of guard ribs 140 to the skin engaging edge 62 is best depicted in FIG. 18, which shows substantially no gap between an end of the guard ribs 140 and the skin engaging edge 62. In other words, the distance between the skin engaging edge 62 and ends of guard ribs 140 is minimal. The portions of the blade 60 in between the guard ribs 140 are allowed to fully engage the skin of the shaver while the guard ribs 140 prevent overexposure of the skin to the skin engaging edge 62.

The guard ribs 144 on the cap member 120 are positioned spaced from the skin engaging edge 62 of the blade 60, as depicted in FIGS. 17 and 18. In the preferred embodiment the guard ribs 140 on the platform member 20, and the guard ribs 144 on the cap member 120 are aligned such that they form evenly spaced rows along the length of the blade cartridge 10.

The embodiments described above provide a number of significant advantages. The present invention provides a blade cartridge arrangement including guard ribs capable of providing an effective means for preventing cuts and abrasions caused by a razor blade being repeatedly passed over the skin of a shaver. The guard ribs provide the portions of the skin engaging edges with a negative blade exposure that prevents overexposure of the blades to the skin, while allowing the remainder of the kin engaging edges of the blade to still provide a close shave.

As yet another advantage, the present invention provides a blade cartridge that is cost effective to manufacture and durable, in that the present invention provides a simple arrangement without moving parts.

A further advantage of the present invention is that it is configured to provide an effective shave on a variety of contours and surfaces.

It should be evident to one of ordinary skill in the art that additional blades and spacers may be added to the embodiments of the present invention described herein to produce a razor blade cartridge having three or more blades. The additional spacers preferably also include protruding members.

Of course, it should be understood that a wide range of changes and modifications could be made to the preferred embodiments described above. It is therefore intended that the present invention is not limited to the embodiments described above, but encompasses any and all embodiments within the scope of the following claims, and equivalents thereof.

What is claimed is:

1. A razor blade cartridge comprising:
a platform member having a blade seat;
a blade disposed on said blade seat, said blade having a skin engaging edge;

a cap member disposed on said blade;
a protruding member positioned on said cap member spaced from said skin engaging edge; and
a second protruding member on said platform member extending to a position proximate said skin engaging edge having substantially no gap between an end of the second protruding member and the skin engaging edge;
wherein a portion of said blade adjacent said protruding member and said second protruding member has a negative exposure relative to a shaving plane tangent to both said protruding member and said second protruding member, and a portion of said blade not adjacent said protruding member and said second protruding member is engageable with the skin of a shaver.

2. The razor blade cartridge according to claim 1 wherein said second protruding member on said platform member is aligned with said protruding member on said cap member.

3. The razor blade cartridge according to claim 2 wherein said second protruding member on said platform member is substantially continuous with said protruding member on said cap member.

4. The razor blade cartridge according to claim 1 wherein said protruding member and said second protruding member each include an arcuate contact surface and is narrow in thickness in a direction along said skin engaging edge.

5. The razor blade cartridge according to claim 1 wherein said cap member includes a plurality of protruding members spaced from said skin engaging edge such that a portion of said blade adjacent each of said plurality of protruding members has a negative exposure relative to said shaving plane, and a portion of said blade not adjacent each of said plurality of protruding members is engageable with the skin of a shaver.

6. The razor blade cartridge according to claim 1 wherein said blade has an aperture for allowing lubricant to flow therethrough.

7. The razor blade cartridge according to claim 6 wherein said cap member has an open portion abutting said aperture on said blade for allowing lubricant to flow therethrough.

8. The razor blade cartridge according to claim 1 wherein said platform member includes a guard member disposed forward of said blade seat so as to form a slot between said blade seat and said guard member.

9. The razor blade cartridge according to claim 8 wherein said second protruding member is attached to said guard member.

10. The razor blade cartridge according to claim 1 wherein said platform member includes a plurality of second protruding members extending to a position proximate said skin engaging edge having substantially no gap between an end of each of said plurality of second protruding members and the skin engaging edge such that a portion of said blade adjacent each of said plurality of second protruding members has a negative exposure relative to said shaving plane, and a portion of said blade not adjacent each of said plurality of second protruding members is engageable with the skin of a shaver.

11. The razor blade cartridge according to claim 1, further comprising:

a handle connected to the razor blade cartridge.

12. The razor blade cartridge according to claim 11, wherein:

the handle is pivotally connected to the razor blade cartridge.

13. The razor blade cartridge according to claim 11, wherein:

13

the handle is releasably connected to the razor blade cartridge.

14. A razor blade cartridge comprising:

a platform member having a blade seat and a guard member; 5
a first blade disposed on said blade seat, said first blade having a skin engaging edge located rearwardly of said guard member; 10
a spacer disposed on said first blade; 10
a second blade disposed on said spacer, said second blade having a skin engaging edge located rearwardly of said skin engaging edge of said first blade; and 15
a cap member disposed on said second blade; 15
said cap member including a protruding member positioned spaced from said skin engaging edge of said second blade; 20
said platform member including a second protruding member extending to a position proximate said skin engaging edge of said first blade having substantially no gap between an end of the second protruding member and the skin engaging edge of the first blade; 25
wherein:
a portion of said second blade adjacent said protruding member has a negative exposure relative to a shaving plane tangent to both said protruding member and said second protruding member, and a portion of said second blade not adjacent said protruding member is engageable with the skin of a shaver, and 30
a portion of said first blade adjacent said second protruding member has a negative exposure relative to said shaving plane, and a portion of said first blade not adjacent said second protruding member is engageable with the skin of a shaver. 35

15. The razor blade cartridge according to claim 14 wherein said spacer includes a third protruding member spaced from said skin engaging edge of said first blade, and extending to a position proximate said skin engaging edge of said second blade having substantially no gap between an end of the third protruding member and the skin engaging edge of the second blade, such that a portion of said first blade and said second blade adjacent said third protruding member has a negative exposure relative to said shaving plane, and a portion of said first blade and said second blade not adjacent said third protruding member is engageable with the skin of a shaver. 45

16. The razor blade cartridge according to claim 15 wherein said protruding member on said cap member, said third protruding member on said spacer, and said second protruding member on said platform member are aligned and are substantially continuous with each other. 50

17. The razor blade cartridge of claim 14 wherein said first blade has an aperture for allowing lubricant to flow therethrough. 55

18. The razor blade cartridge of claim 17 wherein said spacer has an open portion abutting said aperture on said first blade for allowing lubricant to flow therethrough.

19. The razor blade cartridge according to claim 14, further comprising: 60

a handle connected to the razor blade cartridge.

14

20. A razor blade cartridge comprising:

a platform member having a blade seat and a guard member; 5
a first blade disposed on said blade seat, said first blade having a skin engaging edge located rearwardly of said guard member; 10
a spacer disposed on said first blade; 10
a second blade disposed on said spacer, said second blade having a skin engaging edge located rearwardly of said skin engaging edge of said first blade; 15
a cap member disposed on said second blade, said cap member including a protruding member spaced from said skin engaging edge of said second blade; 20
said spacer including a second protruding member spaced from said skin engaging edge of said first blade, and extending to a position proximate said skin engaging edge of said second blade having substantially no gap between an end of the second protruding member and the skin engaging edge of the second blade; and 25
a third protruding member positioned on said platform member extending to a position proximate said skin engaging edge of said first blade having substantially no gap between an end of the third protruding member and the skin engaging edge of the first blade; 30
wherein a portion of said first blade and said second blade adjacent to said second protruding member of said spacer has a negative exposure relative to a shaving plane tangent to both said protruding member and said second protruding member, and a portion of said first blade and said second blade not adjacent said second protruding member is engageable with the skin of a shaver.

21. The razor blade cartridge according to claim 20, further comprising:

a handle connected to the razor blade cartridge.

22. A razor blade cartridge comprising:

a platform member having a blade seat; 5
a blade disposed on said blade seat, said blade having a skin engaging edge; 10
a cap member disposed on said blade; 10
a protruding member positioned on said cap member spaced from said skin engaging edge; and 15
a second protruding member positioned on said platform member extending to a position proximate said skin engaging edge having substantially no gap between an end of the second protruding member and the skin engaging edge, and including a base portion and a contact portion extending from said base portion, said contact portion being thinner than said base portion; 20
wherein a portion of said blade adjacent said protruding member and said second protruding member has a negative exposure relative to a shaving plane tangent to both said protruding member and said second protruding member, and a portion of said blade not adjacent said protruding member and said second protruding member is engageable with the skin of a shaver. 25

23. The razor blade cartridge according to claim 22, further comprising:

a handle connected to the razor blade cartridge.
